Primary Examiner — Randall Gholson*(74) Attorney, Agent, or Firm* — Knobbe Martens Olson & Bear LLP**CLAIM**

The ornamental design for a multi-piece case, as shown and described in the Figures.

DESCRIPTION

FIG. 1 is an exploded three-quarter top view of the multi-piece case with a mobile computing device.

FIG. 2 is an exploded three-quarter bottom view of the multi-piece case with a mobile computing device;

FIG. 3 is a bottom, left-hand-side, front, rear, right-hand-side, and top view of the assembled multi-piece case; and,

FIG. 4 is a bottom, left-hand-side front, rear, right-hand-side, and top view of the assembled multi-piece case enclosing a mobile computing device.

The broken lines such as those showing the mobile computing device are for the purpose of illustrating environmental structure, and form no part of the claimed design.
